UNITED STATES PATENT OFFICE.

RUSSELL H. DAMON, OF LEOMINSTER, MASSACHUSETTS; CLARE B. DAMON AND MURRAY C. DAMON, OF LEOMINSTER, MASSACHUSETTS, EXECUTORS OF SAID RUSSELL H. DAMON, DECEASED, ASSIGNORS TO THE HAIRLIGHT COMPANY, OF LEOMINSTER, MASSACHUSETTS, A CORPORATION OF MASSACHUSETTS.

BARRETTE OR HAIR-RETAINER.

1,152,883.

Specification of Letters Patent. Patented Sept. 7, 1915.

Application filed October 16, 1907. Serial No. 397,647.

To all whom it may concern:

Be it known that I, RUSSELL H. DAMON, of Leominster, in the county of Worcester and Commonwealth of Massachusetts, have 5 invented certain new and useful Improvements in Barrettes or Hair-Retainers; and I do hereby declare that the following is a full, clear, and exact description of the same, reference being had to the accompanying drawings, and to the characters of reference marked thereon, which form a 10 part of this specification.

This invention relates to certain new and useful improvements in barrettes or hair 15 retainers.

The invention contemplates a device of this character where the pin or locking part is attached to the body portion in a way that said pin will have great freedom of 20 movement, the joint being such as to be universal with the required range of movement, so that the whole device may be readily secured to the hair and locked in place.

25 The invention further contemplates the provision of a novel means for locking the free end of the pin or tongue upon the stud carried by the body portion, where the spring or resiliency of the pin is utilized to 30 make a secure fastening, which will hold reliably when in place upon the hair, but which may be readily and conveniently unfastened when it is desired to remove the barrette.

35 In the drawings: Figure 1 is a side elevation, showing the pin or tongue disengaged. Fig. 2 is a top plan view.

Referring to the drawings, 1 designates a body portion or member, slightly curved, 40 and formed of celluloid, horn, tortoise shell, or other suitable material of which devices of this character may be made. Upon the body portion and near one end is formed a staple 2, while at the other end it is provided with a stud 3, having an offset 4. Loosely connected to the staple 2, as clearly shown in Fig. 1, is a tongue or pin 5, also slightly curved and formed of the same material. The pin or tongue is provided at its 45 free end with an elongated opening 6, said opening being adapted to embrace the stud 3 when the device is locked upon the hair. The distance between the opening 6 and the

point of the hinge between the pin or tongue 5 and staple 2, it will be noted, is greater 55 than the distance between the offset 4 of the stud and the said point of hinge, whereby upon bending of either member, though preferably the pin member, the opening 6 will be brought into juxtaposition with the 60 stud 3, and upon cessation of bending pressure, the members will assume their normal position, and the pin will be locked in operative position by said offset portion 4 of the stud. 65

By slightly curving the body portion and the pin or tongue, the tendency of the device when locked upon a tuft of hair will be to force said tongue or pin outwardly, thereby 70 slightly straightening the same, and preventing said tongue from slipping over the offset on the stud 3, thus firmly securing the hair and the barrette itself in position.

The device is applied by simply passing 75 the free end of the tongue or pin through the hair, then bringing the body portion over until the stud engages the inner edge of the opening 6, when the device will be securely locked.

It will be noted that by having the body 80 and pin loosely connected, so that the pin may be swung in an arc on either side of the body as well as in the usual field of movement, the body portion will be left free to hang in any position, and out of the 85 way of the wearer, while the tongue or pin is being passed through the hair. In other words the pin may be said to have a universal movement with reference to the body.

In applying the device the following 90 movements of the pin or tongue relative to the stud occur: When the pin or tongue is brought down on top of the stud, the material of the said pin or tongue will, before pressure is applied to the pin, engage the 95 stud at some little distance inside the opening 6. At this point a slight pressure upon the pin, which results in slightly bowing it, will cause the opening to embrace the stud, and the pressure, such as would be exerted 100 against the pin by the tuft of hair between the body and the pin, would only tend to make the pin embrace the stud more securely, whereas, obviously when it is desired to unfasten the device, the pin is 105 bowed inward to the body, when the easy

disengagement of the pin and stud will be effected.

I have described the device as a barrette or hair retainer, but it will be apparent that 5 the same construction would be equally applicable to a brooch or breast pin.

Claims—

1. A device of the class described, comprising a body portion, a stud rigid with 10 one end thereof, a flexible pin or tongue hingedly connected with the other end thereof, and being formed with an opening in its free end, the distance between the said opening and point of hinge of said pin or tongue 15 being slightly greater than the distance between the said stud and the said point of hinge, whereby upon bending of said pin or tongue the stud will be received in said opening, and the pin or tongue secured from 20 displacement upon cessation of pressure.

2. A device of the class described, comprising a body member, a pin member hingedly attached thereto, and being formed with an opening the walls of which are substantially unyielding, one of said members being flexible, a stud rigid with the body member and having its upper portion offset 25 or inclined toward said point of hinge, the

length of the pin member between its opening and its point of hinge being greater than 30 the distance between the top or offset end of the stud and the point of hinge, whereby upon exertion of bending pressure upon the said flexible member the stud may be inserted into said opening of the pin, and 35 locked therein to secure the pin by the offset portion of the pin by the offset portion of the stud upon resumption of the flexible member of its normal position.

3. A device of the class described, comprising a body portion; a stud rigidly mounted on one end thereof, said stud having an offset; a longitudinally-disposed staple-shaped member located at the opposite end of the body portion; and a flexible 40 tongue hinged to said staple-shaped member, said tongue being formed of a flat strip and provided adjacent to the free end with an elongated opening adapted to receive the stud when the body of the tongue is flexed, 45 the tongue being held by the offset of the stud when it resumes its normal shape.
